EDGAR J. GOLDSMITH AND HUGO GOLDSMITH, OF CINCINNATI, OHIO, AS-SIGNORS TO P. GOLDSMITH'S SONS, OF CINCINNATI, OHIO, A FIRM.

SUPPORTING MECHANISM FOR PUNCHING-BAGS.

SPECIFICATION forming part of Letters Patent No. 735,750, dated August 11, 1903.

Application filed April 18, 1903. Serial No. 152,401. (No model.)

To all whom it may concern:

Be it known that we, EDGAR J. GOLDSMITH and HUGO GOLDSMITH, citizens of the United States, and residents of the city of Cincinnati, in the county of Hamilton and State of Ohio, have invented certain new and useful Improvements in Supporting Mechanism for Striking-Bags, of which the following is a specification.

10 Among the various objects of our invention there should at this point in the specification be noted, first, a remarkable portability of structure; secondly, great compactness of the parts; thirdly, a structure whose parts 15 at will are readily separated and again readily united; fourthly, horizontal adjustability of the structure which immediately supports the bag; fifthly, vertical adjustability of the same structure; sixthly, adjustability for varying the length of the travel of the bag; seventhly, a convenient means when the cord which supports the bag is lengthened or shortened for enabling the bag to strike its abutment centrally and in a desired position.

25 Other objects additional to these, some of them consequential thereto, will be herein-after apparent.

The several features of our invention and the several features resulting from their use 30 conjointly or otherwise will be apparent from the following description and claims.

In the accompanying drawings, making a part of this specification, and in which similar letters of reference indicate corresponding parts, Figure 1 represents in perspective a view of the mechanism immediately connected with the bag and the arm and part of the means of the preferred means for supporting the same. Fig. 2 represents a top 35 plan view of mechanism illustrating our invention, excepting means for supporting the upright or vertical shaft on which the supporting-bracket is pivoted. Fig. 3 represents a side elevation of this mechanism. In the central portion of this view is shown a modification of the means adjacent to the abutment and for supporting the latter. Fig. 4 represents a top view of the preferred means 40 for supporting the said vertical shaft. Fig. 5 represents a front elevation of the device shown in Fig. 4. Fig. 6 represents in verti-

cal central section a single means for upholding the horizontal shaft which supports the striking-abutment and the striking-bag and which allows the horizontal shaft to be moved 55 in a horizontal plane. Fig. 7 is a view in perspective, showing the striking-bag and its supporting mechanism upheld by the frame of a door.

We will now proceed to describe our invention in detail.

A indicates the striking-bag; B, the cord which supports it. This cord is connected to the bag in any suitable manner.

C indicates the abutment, against the outer 65 side of which the bag strikes. The abutment is provided with a downward extension D, whose lower end is of much less diameter than the diameter of the abutment C. For the purpose of economizing metal 70 and diminishing unnecessary weight the upper portion of this extension is also of much less diameter than that of the abutment. The lower end of the abutment has a vertical passage D², through which the cord B extends. To allow the cord to easily oscillate as the bag is moved back and forth, the passage enlarges in a tapered form, making an inclined annular side D³. Above this passage the vertical opening D² enlarges, forming the chamber D⁴, having the annular shoulder D⁵. In order to more readily reach the rope immediately above the shoulder D⁵, we provide an opening D⁶, extending through the wall of the extension and to the chamber 80 85 D⁴. Thus when the cord of the bag A is to be connected to the part D the upper end of the rope is passed up through the passage D² and knotted at a suitable point of it above the shoulder D⁵ and then dropped, so that 90 the knot B² rests upon the shoulder D⁵. The lower edge D⁶ of the passage D² is rounded, as shown. The enlargement of the passage-way D² and the rounded edge D⁶ greatly facilitate the easy turning and flexing of the 95 cord B and assist in preventing the cord being cut or broken at this point of flexure. Thus the duration of the cord is lengthened. The extension D may be united to abutment C in any desired manner; but it is preferably 100 cast in one with the abutment C. The outer side C² of the abutment is inclined, as shown.

As it is desirable to shorten and lengthen the cord B below the extension D, so as to vary at will the length of the arc in which the bag travels and the consequent number of the oscillations of the bag, the side of the abutment is made correspondingly long from top to bottom. Thus the preferred width vertically of this side C² is about four inches. Such an extension enables the abutment C to duly receive the impact of the side of the bag when the latter is struck and swings up. To best accomplish this, the plane of the inclination of the side C² when extended down will just meet the point or edge D⁶. This accommodation—viz., this extended flat side C², inclined, as shown—offers special advantages over the ordinary ring-abutment, whose height is very little and whose outer surface is an arc of a circle. In the latter instance there is only one length of cord, with which the bag will strike the ring exactly at its side center—that is, at the end of the transverse axis of the bag and at right angles to that axis of the bag which is the extension of the axis of the cord; but with an abutment of the shape which we present during every variation of the length of the cord from the longest to the shortest condition of length (extension) the center of the bag will strike the abutment in the same manner and the said transverse axis of the bag will be at right angles to the up and down inclination of the side C². Under these conditions we are not only able to provide a very varied length of swing for the bag, but also to have the bag in every instance strike correctly. In consequence the bag will not be wrenched or strained; but if it is so strained its connection with the cord is strained when it strikes the abutment in any other manner than that last described. We are therefore by this feature of our invention enabled to increase the variation in the length of the cord of the bag and at the same time prolong the duration of the bag and its efficiency and also accelerate its rebound by causing it to strike at the point of its largest diameter.

It is to be understood that the primary object in varying the length of the swing of the bag is to vary the speed of its movement. The shorter the arc the greater the speed, and vice versa.

We uphold the abutment C by a suitable support. A preferred one consists of the single arm E, provided with branches E² E². These branches E² E² may be separable from the arm E and suitably fastened thereto. One mode of such separable connection is illustrated in Fig. 1. Here each branch is connected to a bearing-sleeve B E². This sleeve is slipped upon the rod E and secured in place by a set-screw N E². Where such a construction is present, the abutment and its branches E² E² can be readily removed from the arm E and readily replaced thereon. The foot of one of these branches is duly connected (shown as bolted) to one outside portion of

the abutment C, and the foot of the other branch E² is secured to an opposite portion of the abutment, substantially as shown. 70 The branches may be integral with the arm E. Such a condition of construction is shown in Figs. 2, 3, and 7. When preferred, the branches may be shorter and more centrally connected to the abutment, substantially as 75 shown, by the set of inner branches at E³. There the branches E² E² are respectively connected at E⁴ E⁴ to a part of the abutment adapted to receive them. It is to be understood that when the shorter branches are 80 used the longer branches will be omitted, and vice versa. In any case, no matter how connected to the abutment, the arm E extends back and is duly supported in a bracket or brackets which admit of it being moved horizontally from the right to the left, or vice versa. A simple mode of doing this is illustrated in Fig. 6. Here the arm E has a vertical portion H², having shoulders K³. A bracket M, screwed or otherwise secured to the woodwork at the 90 part or parts M², receives the part H² of the bracket. A set-screw N of the bracket M enables the arm E to be set after being located at the correct part of the horizontal arc in which it moves; but the preferred mode of 95 adjustably connecting the arm to the supporting woodwork, &c., is as follows: There are two brackets M M. The vertical shaft H is received in them. The bracket-arm E by means of a sleeve or bearing E⁵ embraces 100 the shaft H and to admit of readily being secured thereto or detached therefrom and at a desired height on the shaft H. This sleeve or bearing E⁵, which embraces the bar, has a securing bolt or bolts E⁶. Although the lower 105 end of the shaft H may be diminished and have shoulders K³ and be set in a bracket, as exemplified in Fig. 6, we preferably allow the shaft H of full size to be within the lower bracket and uphold the shaft H by a collar 110 K, fixed on the shaft at the desired point along the vertical length of the latter. The bracket K will rest and turn upon the lower bracket. Where the shaft H is long and of greater length than the distance between the 115 bottom of the lower bracket and the top of the upper bracket as placed, the shaft carrying the arm E fixed to it can be adjusted vertically by changing the position of the collar K thereon, and thus the arm E will be 120 raised or lowered without disturbing the bolts E⁶ E⁶; otherwise to lower or raise the arm E for adjusting the frame and bag vertically to suit the different heights of the individuals using same the bolts E⁶ E⁶ must 125 be loosened and after such adjustment then be tightened. The preferred construction of the means for supporting the arm where two brackets M M are employed is well illustrated in Fig. 7. So far as the construction of the 130 sleeve or bearing E⁵ relative to the arm E is concerned the sleeve may receive the end of the arm, as in Fig. 1, or be integral therewith, as illustrated in Fig. 2.

The mechanism is set up and operated as follows: The bracket or brackets M are affixed to the woodwork or equivalent support. The shaft H is located in the bracket or brackets M. When the constructions shown in Fig. 2 are present, the collar K and the arm or shaft E are set at desired points on the shaft or upright II. The abutment is then moved out to the desired position, the arm E moving with the shaft H to accommodate this movement. Then the set-screws N of the bracket-arms are tightened and the shaft fixed in position. Thus the abutment will be made stationary. Where the device shown in Fig. 6 is used, the set-screw N is tightened after the abutment has been put into position. The extent of the swing of the bag and its consequent rapidity of movement will be regulated by the length of the cord between the bag and the extension D, as aforementioned.

Our device is very portable and convenient. Obviously it accomplishes all of the objects which it is designed to do and as enumerated in the opening portion of this specification.

Our mechanism can be readily connected to the side of a door-frame of a closet or other compartment. When it is to be used, the arm E, with abutment C, can be swung out and set. It is then ready and can be used so long as desired. When not in use, it can be swung back and the door closed. As the abutment and arm E can be, so to speak, "moved" against the door or wall, so as to lie close to it and out of the way when not in use, it also offers in this way much of advantage to young men and others possessed of a limited amount of room-space. One illustration of such application is seen in Fig. 7.

When we mention the branches E², we mean "subarms," and by the term "subarms" we mean these branches.

What we claim as new and of our invention, and desire to secure by Letters Patent, is—

1. In a striking-bag apparatus, an abutment having an inclined, wide, annular side, a rigid central extension below, a striking-bag, a cord connecting the bag to the lower end of this extension, and means for enabling the cord to be lengthened or shortened as desired, substantially as and for the purposes specified.

2. In a striking-bag apparatus, an abutment having a wide, flat, inclined annular side, a rigid central extension below, a striking-bag, a cord connecting the bag to the lower end of this extension, the extension containing a chamber, and having a side opening from the outside of it (the extension) to this chamber, substantially as and for the purposes specified.

3. In a striking-bag apparatus, an abutment having a wide, circular inclined side C², and a rigid extension or part D below, centrally disposed, this extension having chamber D⁴, and the passage D⁶, the side C² being inclined relatively to the lower end of the extension,

substantially as and for the purposes specified.

4. In a striking-bag apparatus, an abutment having a flat annular side, a rigid central extension downward from the abutment, the extension having a passage at its end for the reception of the cord, said passage being downwardly enlarged, the lower edge of the extension around this passage being rounded, the side of the abutment against which the bag strikes being inclined, substantially as and for the purposes specified. 70

5. In a striking-bag apparatus, a circular abutment having a wide inclined side C², and a rigid extension or part D, centrally disposed, the extension having chamber D⁴ and the passage D⁶ thereto, a passage D² at the free end portion of the extension having outwardly and downwardly inclined side, the edges D⁶ of the extension being rounded, the side C² being inclined relatively to the lower end of the extension, substantially as and for the purposes specified. 75

6. In a striking-bag apparatus, a circular abutment having a flat inclined side, a rigid central extension downward from the abutment, a striking-bag, a cord connecting the bag to the lower end of this extension, this abutment and the extension formed in one piece, substantially as and for the purposes specified. 90

7. In a striking-bag apparatus, an abutment and means for holding the cord which upholds the bag, an arm connected to the abutment, and means at the other end of the arm adapted to support the arm and enable it to move so that that end of the arm which carries the abutment moves in the line of a circle, substantially as and for the purposes specified. 100

8. In a striking-bag apparatus, an abutment and means for holding the cord which upholds the bag, an arm carrying at its outer end the abutment, and at its inner end connected to a vertical shaft supported by a bracket, adapted to allow the vertical shaft to turn therein, and means for setting the vertical shaft rigidly, at the desired plane of rotation, substantially as and for the purposes specified. 110

9. In a striking-bag apparatus, an abutment and means for upholding the cord which upholds the bag, an arm carrying at its outer end the abutment, and at its inner end connected to a vertical shaft supported by a bracket, adapted to allow the vertical shaft to turn therein, and means for preventing the vertical shaft from slipping down through the bracket, and means for setting the vertical shaft rigidly, at the desired level of rotation, substantially as and for the purposes specified. 115

10. In a striking-bag apparatus, an abutment and means for upholding the cord which supports the striking-bag, an arm carrying at its outer end the abutment, and at its inner end provided with a sleeve, a vertical shaft

embraced by this eye, means for fixing the bearing fast to the shaft at a desired point thereon, and means for supporting and for holding the shaft in place, substantially as and for the purposes specified.

11. In a striking-bag apparatus, an abutment and means for upholding the cord which supports the striking-bag, an arm carrying at its outer end the abutment, and at its inner 10 end provided with a sleeve, a vertical shaft embraced by this eye, set-screws of the sleeve adapted to bear against the shaft, and means for supporting and for holding the shaft in place, substantially as and for the purposes 15 specified.

12. In a striking-bag apparatus, an abutment and means for upholding the cord which supports the striking-bag, an arm carrying at its outer end the abutment, and at its inner 20 end provided with a sleeve, a vertical shaft embraced by this sleeve, means for fixing the sleeve fast to the shaft at a desired point thereon, and brackets for holding the shaft, and means for preventing it moving vertically except as desired, substantially as and 25 for the purposes specified.

13. In a striking-bag apparatus, an abutment and means for upholding the cord which supports the striking-bag, an arm carrying at 30 its outer end the abutment, and at its inner end provided with a sleeve, a vertical shaft embraced by this sleeve, means for fixing the sleeve fast to the shaft at a desired point thereon, and brackets for holding the shaft, 35 and the collar embracing the shaft and adapted to be fixed thereon, at the desired point, substantially as and for the purposes specified.

14. In a striking-bag apparatus, an abutment and means for upholding the cord which 40 supports the striking-bag, an arm carrying at its outer end the abutment, and at its inner end provided with a sleeve, a vertical shaft embraced by this eye, set-screws of the sleeve 45 adapted to bear against the shaft, brackets for holding the shaft, and a collar embracing the shaft above a bracket and set-screw for fixing it thereon, substantially as and for the purposes specified.

15. In a striking-bag apparatus, a circular abutment having an inclined side, a rigid central extension downward from the abutment,

a striking-bag, a cord connecting the bag to the lower end of this extension, an arm connected to the abutment, and means at the 55 other end of the arm adapted to support the arm so that the end of the arm which carries the abutment moves in the arc of a circle, substantially as and for the purposes specified.

16. In mechanism for supporting a striking- 60 bag, a striking-bag, an abutment, a horizontal arm, subarms at their lower ends adapted to support the abutment, and at their upper end provided with means for engaging the horizontal arm, means at the other end of the 65 horizontal arm adapted to support the arm and enable it to move so that that end of the arm over the abutment moves in the line of a circle, substantially as and for the purposes specified.

17. In mechanism for supporting a striking- bag, a striking-bag, an abutment, a horizontal arm, subarms at their lower ends adapted to support the abutment, and at their upper end provided with bearing, adapted to embrace 75 and slide upon the horizontal arm, and means for setting the same on this arm, substantially as and for the purposes specified.

18. In a striking-bag apparatus, an abutment having a flat annular side, a rigid central extension downward from the abutment, a striking-bag, a cord connecting the bag to the lower end of this extension, the inclination of the side of the abutment being in a plane, which if extended would meet the free 85 end of the extension, substantially as and for the purposes specified.

19. In a striking-bag apparatus, an abutment having a wide flat annular side, a rigid central extension downward from the abut- 90 ment, a striking-bag, a cord connecting the bag to the lower end of this extension, the inclination of the side of the abutment being in a plane, which if extended would meet the free end of the extension, and means for enabling the cord to be lengthened or shortened 95 as desired, substantially as and for the purposes specified.
